UNITED STATES PATENT OFFICE.

RICHARD JOHN FRY, OF BRUNSWICK, NEAR MELBOURNE, VICTORIA, AUSTRALIA.

APPARATUS FOR THE TRANSMISSION OF POWER.

No. 918,034.

Specification of Letters Patent.

Patented April 18, 1909.

Application filed August 7, 1907. Serial No. 387,475.

To all whom it may concern:

Be it known that I, RICHARD JOHN FRY, a subject of the King of Great Britain and Ireland, residing at Barkly street, Brunswick, near Melbourne, in the State of Victoria, Commonwealth of Australia, have invented certain new and useful Improvements in Apparatus for the Transmission of Power, of which the following is a specification.

This invention provides an improved apparatus for the transmission of manual and other power, which apparatus, although simple and comparatively inexpensive to manufacture, will be very effective for use with cranes, grubbing machines, for lifting weights, for locomotion or propulsion of vehicles, and for a number of other purposes in which a continuous transmission of power applied is desired.

The apparatus consists of two (or more) wheels constructed preferably of metal and secured at their centers at a suitable distance apart to a winding drum, and each wheel having peripheral teeth thereby forming a double endless ratchet. The winding drum, which acts as the axle, may protrude through either or both of the ratchet wheels, but ordinarily it projects sufficiently through both to enable a bridle and suitable anchoring or retaining gear to be conveniently affixed thereto. An upwardly curved standard having a foot-piece extends from the anchor plate—to which it is connected by convenient means as bolts passing through its foot-piece—to a point intermediate the two ratchet wheels, and it provides means for the pivoting of the operating lever. The standard to which the lever is pivotally fastened has sufficient spring to allow of a slight vertical action in addition to a right and left motion of the lever, while the torsional strain on this standard retains the lever firmly in operative position and in engagement with the ratchet teeth. The operating lever is constructed with two jaws adapted to engage with the teeth of the ratchet wheels, engaging one wheel with the forward motion and the other wheel with the backward motion, or alternately upward and downward.

In the accompanying drawings there is illustrated a machine constructed according to my invention and employed for extracting trees and stumps from the ground.

Reference will now be made to these draw-

ings in order that the invention, its mode of operation, as well as its applicability to analogous uses will be clearly understood.

Figure 1 is a side elevation of the machine, and showing the operating lever in vertical section. Fig. 2 is a plan, and Fig. 3 a front elevation of the parts illustrated in Fig. 1.

In these views 1—1 designates wheels, which are constructed of suitable material as metal, secured at their centers at a desired distance apart to a winding drum or axle 2. Each of these wheels 1 has peripheral teeth 3, thereby forming a double endless ratchet in which the teeth of one wheel are positioned in advance of the corresponding teeth of the other wheel, that is to say the radial face of a tooth of one wheel is opposite to and corresponds in position with the space between two teeth of the other wheel. The winding drum or axle 2 passes sufficiently through the centers of each of the wheels 1 to enable a bridle 4 to be conveniently affixed thereto.

5 is a flat anchor plate affixed to the bridle 4 by means such as the bolts 6, and this plate 5 serves to give the bridle the weight necessary in a machine of this description, and in addition it enables the gear designed for the operating lever pivot or fulcrum to be suitably attached.

7 is an upwardly curved standard having therein a twist 8 and affixed to the anchor-plate 5 by means of bolts 9 or the like passing through its foot-piece 8^a. The standard 7 extends from the anchor-plate to a point intermediate the two ratchet wheels 1, and it has its rear end furnished with a recess 10 into which the operating lever 12 movably fits. This lever has a hole drilled therein in which a vertical pin 11 is designed to drop and pass through the recessed end of the standard or lever support 7. By this means a simple though effective pivot or fulcrum for the lever 12 is formed, and the torsional strain of the standard 7 caused by the twist 8 therein tends to exert sufficient downward pressure on the lever 12 to retain it in an operating position, while allowing a slight vertical action in addition to a free right and left motion of the lever. This lever 12 is constructed with two jaws or bearing faces 13, each of which engages with the teeth of a ratchet wheel 1 on the forward or rearward movement of the operating lever 12. The vertical pin 11 which

forms the lever pivot is furnished with a ring 14 for the purpose of enabling it to be removed without difficulty, whenever required.

5 15 represents a framing or stand—one provided on each side—designed to support the ratchet wheels 1, when the machine is positioned ready for operation (as illustrated in Fig. 1), sufficiently above the 10 ground to allow of the unhindered rotation of the wheels and the winding drum 2 when operated by the lever 12. When, however, this anchor-plate 5 has been raised in order that the machine may be moved from place 15 to place, the stands or framings 15 are lifted above the ground and the machine is free to travel on its toothed revoluble wheels 1.

The numeral 17 indicates that any chain, 20 rope or the like can be conveniently affixed to the forward end of the anchor-plate 5 having an aperture 16 for the purpose of drawing the machine, for example from one stump to another.

In operation one end of the hauling rope 25 or chain 18 is affixed to the winding drum or axle 2, while its other end is connected to the stump, tree or other object to be extracted or moved. By operating the pivoted lever 12 forwardly and backwardly, one of 30 the jaws 13 engages with the teeth 3 of one of the ratchet wheels 1 on the forward travel, while the other jaw 13 engages with the teeth of its corresponding ratchet on the rearward movement of the lever. By 35 this means a continuous forward motion is given to the winding drum without any pawls, dogs or other holding means being required as the jaws 13 of the lever are firmly retained in engagement with the faces 40 of the teeth 3 by the spring and torsional strain of the upwardly curved standard or support 7 to which the lever is pivoted. The spring in this support is such that it enables a slight vertical movement of the lever 12 45 required, to work the machine, in addition to the usual approximately horizontal motion, and for the purpose of releasing the strain on the hauling rope 18 if at any time desired, the machine is simply worked backwardly. It will be readily understood that 50 the lever 12 can be so constructed that leverage may be exerted from either or both sides of the machine. Power may also be applied by the provision of cog wheels or endless 55 chain gearing according to the class of work engaged in. For applying the power to wheels a chain-wheel of desired diameter and pitch can be affixed to one of the ratchet wheels 1 for the operation of an endless 60 chain gearing.

In practice the ratchet wheels 1 may be constructed with keyways, and be secured to the winding drum by tapered keys for the purpose of enabling the distance apart of the 65 two ratchet wheels to be readily and con-

veniently adjusted. In this case, the pivoted operating lever 12 would be furnished with a series of jaws 13 at required distances apart. In a simple form of the machine one ratchet wheel only may be employed in conjunction with the apparatus previously described, for the successful operation of which a pawl, however, would be required. This and sundry modifications, however, as well as variations in the details can be made 75 within the scope of the invention.

What I claim as new and desire to secure by Letters Patent of the United States is:—

1. In apparatus of the class indicated, the combination of revoluble wheels having peripheral teeth and secured centrally to an axle or winding drum, a pivoted operating lever having jaws adapted to engage with the teeth of said wheels, and a standard to which said lever is pivoted and retained in 80 engagement with said teeth by the torsional strain of such standard, substantially as and for the purposes set forth.

2. In apparatus of the class indicated, the combination of two ratchet wheels secured at 90 their centers to an axle or winding drum, an operating lever pivoted intermediate the ratchet wheels and constructed with a plurality of jaws adapted to engage with the ratchet teeth, a bridle attached to the axle or 95 winding drum, and an anchor-plate affixed to said bridle, substantially as and for the purposes set forth.

3. In apparatus of the class indicated, the combination of two ratchet wheels 1 secured 100 at their centers to an axle or winding drum 2, an operating lever 12 pivoted intermediate the ratchet wheels and constructed with a plurality of jaws 13, and a standard or support 7 the torsional strain of which retains 105 said lever 12 in engagement with the ratchet teeth, substantially as described and illustrated and for the purposes set forth.

4. In apparatus of the class indicated, the combination of two ratchet wheels 1 secured 110 at their centers at convenient distances apart to an axle or winding drum 2, a pivoted operating lever 12 adapted to engage with the teeth of one ratchet wheel on the forward motion and the teeth of the other on the rearward travel, a bridle as 4, anchor-plate as 5, and framings or stands as 15, substantially as described and for the purposes set forth.

5. In apparatus of the class indicated, the combination with two ratchet wheels secured 120 at their centers to a winding drum, of an upwardly curved spring standard or support 7 having a foot-piece 8^a, and a recess 10 formed in one end thereof, an operating lever 12, which has a plurality of jaws or 125 bearing faces 13, adapted to engage with the teeth of the ratchet wheels in the manner described, said lever being pivotally mounted in said recess 10 and retained in an operating position by the torsional strain of 130

said standard 7, substantially as described and illustrated and for the purposes set forth.

6. In an apparatus of the character described, the combination with a revoluble wheel having peripheral teeth and secured centrally to an axle, of a pivoted operating lever having a jaw adapted to engage with the teeth of the ratchet wheel, and a stand-
ard to which said lever is pivoted and re-

tained in engagement with said teeth by the torsional strain of such standard.

In witness whereof I have signed this specification in the presence of two witnesses.

RICHARD JOHN FRY.
